CIGARETTE TRAY

John M. Kisselle, Detroit, Mich.

Application December 12, 1938, Serial No. 245,136

20 Claims. (Cl. 206—19.5)

This invention relates to a cigarette tray and has particularly to do with a tray to be used on a moving vehicle.

The use of cigarettes by passengers in automobiles is constantly increasing and accommodations for these smokers has presented a problem. If an inside ash tray is provided, this tray must be emptied at frequent occasions. Many smokers dispose of their cigarette butts by throwing them from a window of the vehicle. It often happens, however, especially in cold weather, that when the window is opened just a crack from the top and the cigarette thrown therefrom, it will fly back into the car, sometimes unnoticed, and cause damage to the upholstery and clothing.

It is an object of the present invention to provide a receptacle for ashes and cigarette butts which may not only be used for retaining the ashes but also for ejecting them from the vehicle.

It is a further object of the invention to provide a cigarette receptacle which will positively eject cigarettes from the vehicle without danger of their flying back. An additional object has to do with a novel design of a tray whereby it will be swept clean by the wind each time it is operated.

Other objects and features of the invention having to do with details of construction and operation, and especially with the snap action of the ejector, will be brought out in the following description and claims.

Briefly, my invention is accomplished by movably mounting a receptacle adjacent a window of the vehicle in such a manner that when the window is opened by a passenger the tray will be moved quickly through the window opening so that it will dump the contents of the tray.

In the drawings:

Fig. 1 is a side elevation of an embodiment of my invention.

Fig. 2 is a cross section taken on the lines 2—2 of Fig. 1 and illustrating in dotted lines, the final position of the tray in the ejection movement.

Fig. 3 is a sectional view of a modification of my invention.

Fig. 4 is a plan view of the tray used in Fig. 3 showing a novel construction.

Fig. 5 is a diagrammatic illustration of the preferred operation of the tray.

Fig. 6 is a vertical section of another modification of a tray.

In Fig. 1 of the drawings an ash tray constructed in accordance with the present invention is shown attached to the header of a door. The header consists of a stop flange 10, a top rail 11, and on the inside is a finishing strip 12

and a garnish molding 13. On the outside is a finishing molding strip 14 and between the moldings 13 and 14 is the usual window channel 15 for receiving the top edge of a window panel 16.

The ash tray device consists of a housing indicated generally at 17 and an ash tray 18 mounted within said housing. The housing 17 has two outwardly extending lugs 19 near the top thereof which are used to fasten the housing to the garnish molding 13. Screws 20 are used for this purpose. The housing 17 consists essentially of a thin plate 21 which extends downwardly and toward the window panel 16. The side of the housing toward the panel is open and in the plate 21 at the top portion is a horizontal, elongated opening 22. At the lower outside edge of the housing of the plate 21 are formed hinge portions 23.

The tray 18 consists of a tray portion 24 and a supporting portion 25. The supporting portion which consists of a thin plate having a slight curvature, as shown in Fig. 2, is provided with hinge portions 26. The hinge portions 23 and 26 are each formed with a turned over portion through which extends a pin 27. It will thus be seen that the tray is pivotally mounted on the housing. A spring 28 engages the tray and the housing and urges the housing toward the window panel. A short extension 29 from the plate 25 on the tray is adapted to engage a hooked extension 30 which extends from the housing plate 21 after the tray has moved a certain distance. It will be noted that the ash tray extends upwardly at a point 31 so that it contacts the inside of the channel 15.

In the operation: When the ashes or a cigarette butt 32 are placed in the tray 24, through the opening 22 of the housing, the window panel 16 may then be lowered. As the panel is lowered the tray will stay substantially in the position in which it is shown in Fig. 2 until the top edge of the panel gets to a point near the hinge pivot 27. At this point the tray 24 will move quickly outward through the opening in the window to a position shown by the dotted lines in Fig. 2, so that the cigarette and the ashes will be dumped from the tray and thrown positively away from the window opening. Since the portion 31 of the tray contacts the inside of the channel 15, the tray will remain substantially closed from any drafts until the window has been lowered to a point where the tray may move quickly through the opening. When the window is again raised, the tray will be returned against the ac-

tion of the spring 28 to its position shown in the full lines of Fig. 2.

In Fig. 3 a modification of the invention is shown. In this modification an arm 35 is supported on and depends from the garnish molding 13. Pivoted on a lower portion of this arm at 36 is an ash tray which consists of a tray portion 37 and a supporting arm portion 38. The arm portion is pivoted at 36 to the arm 35. A spring 39 acts from the arm 35 to urge the tray 37 toward and against the window panel 16. A plan view of the tray 37 is shown in Fig. 4. This tray is substantially triangular in cross section and has an overhanging flange 40 at one side. The end of the tray which is facing the front of the vehicle is provided with a hole 41 and the tray itself is preferably streamlined at the rear end as shown at 42. In the operation of this device, as the window panel 16 is lowered, the tray will be moved quickly through the window opening by the action of the spring 39 and the wind from the moving vehicle will flow through the hole 41 to wipe or clean the tray. The tray will be moved back to the solid line position of Fig. 3 by a raising of the window panel as before.

An important feature of the invention is the action of the tray as it passes through the window opening. This has been described in connection with the modifications shown in Figs. 1 to 4 and is particularly brought out in the modification of Fig. 6 and the diagrammatic presentation of Fig. 5. The modification of Fig. 6 consists essentially of a depending arm 45 which supports a tray 46 which is pivoted thereto at 45a. A lever 47 is pivoted at 48 and connected to the tray by a link 49. This lever contacts the window panel at its top end and is urged against the window panel by a spring 50.

The operation of the tray is depicted diagrammatically in Fig. 5. It will be seen that as the window panel 16 is lowered to the respective points 1, 2 and 3, the movement of the tray 46, as shown by the points 1, 2 and 3, on the circle is very slight. As the panel is lowered from the point 3 to the point 4, the movement of the tray 46 is extremely rapid as is shown by the long arc 3 to 4 on the circle. The position of the tray at this point 4 is shown in dotted lines. Further movement of the panel to points 5 and 6 will complete the movement of the tray through the window opening.

It should be understood that my invention is not limited in its application to the embodiments shown. It may be adapted to any type of closure where a movable member is moved to expose an opening.

What I claim is:

1. A cigarette and ash ejector device in combination with a movable panel located in an opening of an automobile body, comprising a mounting means located adjacent said panel opening in the interior of said body, a tray movably mounted on said mounting means and movable through said opening, and means connected to said tray for engaging said panel to cause said tray to pass through said opening and to shift relative to the mounting means to dump its contents outside said body upon opening movement of said panel.

2. A cigarette and ash ejector device to be used with a movable window panel which normally closes an opening, said ejector comprising a tray for receiving said ash, supporting means at the margin of said window opening, means connecting said tray and said supporting means, means

normally urging said connecting means against said window panel when closed, said connecting means being so shaped and arranged that, upon movement of said window panel a predetermined distance, said tray will be snapped through said opening to dump its contents.

3. A cigarette and ash ejector device to be used with a movable panel which normally closes an opening, said ejector comprising a tray for receiving said ash, and means at the margin of said window opening comprising an enclosed housing having an opening therein for supporting said tray whereby said tray is open to said housing opening to permit receiving of ash, and whereby a portion of said tray is positioned adjacent said window margin to close the tray from said window opening, and means on said tray whereby the opening of said window panel a predetermined distance will cause said tray to be projected through said opening to dump its contents.

4. A cigarette and ash ejector device to be used with a movable window panel which normally closes an opening which comprises a tray for receiving said ash, means adjacent the opening of said window and supported at the margin of said opening for movably mounting said tray whereby said tray may pass through said opening and dump, means normally urging said tray to pass through said opening, said tray being designed to bear against said window panel when closed, whereby moving said window panel away from said opening will result in said tray passing through said opening to dump its contents.

5. A cigarette and ash ejector device in combination with a movable window panel which normally closes an opening, said device comprising an ash receiving tray movably mounted and movable through said opening and means biasing said tray against said panel whereby opening movement of said panel a predetermined distance will cause said tray to be moved through said opening to dump the contents, said tray being provided with an opening at one end thereof to permit air to sweep through the tray to clean the same.

6. A cigarette and ash ejector device to be used with a movable window panel which normally closes an opening, said ejector comprising a tray for receiving said ash, means supported adjacent an interior margin of said window for mounting said tray, means pivotally mounting said tray to said supporting means, and means connecting said supporting means and said window panel to move said tray through said opening to a dumping position upon an opening movement of said panel.

7. A cigarette and ash ejector device to be used with a movable panel located in an opening comprising a mounting means adjacent said panel opening, a tray movably mounted on said mounting means, means connected to said tray for engaging said panel, and resilient means for urging said last named means against said panel whereby a moving of said panel from said opening will cause said tray to pass through said opening and dump its contents.

8. A cigarette and ash ejector device to be used with a movable panel located in an opening comprising a mounting means adjacent said panel opening, a tray movably mounted on said mounting means, control means connected to said tray for engaging said panel, and resilient means for urging said control means against said panel, said means being so arranged that after said

panel is opened a predetermined distance said tray will pass quickly through said opening from an upright position to dump its contents, and a closing movement of said panel will move said tray quickly through said opening to its upright position.

9. In an automobile body, a cigarette and ash ejector comprising a supporting means mounted adjacent the margin of a side window panel opening in said body, retaining means for said ashes or butts movably mounted on said supporting means, and lever means actuated by an opening movement of the window panel for moving said retaining means relative to said supporting means to a dump position outside said opening.

10. In an automobile body a cigarette and ash ejector device mounted adjacent the margin of a window panel opening in said body, said device comprising retaining means for ashes or butts, and means for moving one portion of said retaining means relative to the other portion to a dump position through and outside said opening, said tray being so shaped and positioned when dumping as to permit air currents caused by movement of the body to assist in the removal of material in said tray.

11. In combination, an automobile body having a window opening, a movable panel to close said opening, and a cigarette and ash ejector device comprising an outer container mounted adjacent a margin of said panel and having a receiving opening available from the interior of said car, and an inner container mounted in said outer container and movable from a receiving position within said outer container to a dump position away from the interior of said car.

12. In combination, an automobile body having a window opening, a movable panel to close said opening, and a cigarette and ash ejector device comprising an outer mounting bracket adjacent said panel having a receiving opening available from the interior of said car, and an inner container mounted in said bracket and movable, when said panel is open, from a receiving position in said bracket to a dump position away from the interior of said car.

13. A cigarette and ash ejector device in combination with a movable panel normally closing an opening in an automobile body, said device comprising an ash tray, means movably mounting said ash tray and arranged to permit movement of said tray through said opening, and means put in motion by movement of said panel to actuate said tray to dumping position.

14. In combination, an automobile body including a window opening and a movable panel to close said opening, and an ash receiving and ejecting device mounted on a part of said body, means movably mounting said device to render it movable through said opening upon relative movement between said panel and opening, at least a portion of said device being movable to ash ejecting position when said device has been moved through said opening.

15. In an automobile body having a window opening and a movable panel to close said opening, an ash receiving and dumping device carried by said body, means mounting the device

cooperating with said panel to render the device movable to a receiving position inside said body by closing movement of said panel and through said opening and outside said body to a dumping position by opening movement of said panel.

16. An ash receiver comprising a housing shaped for mounting adjacent an opening in an automobile body, filling and discharge openings formed in said housing, a tray movably mounted in said housing and normally positioned to cooperate with said filling opening, means projecting from said housing for moving said tray from said normal position to a position cooperating with said discharge opening to dump the contents of said tray, and resilient means normally tending to move said tray toward one of said positions.

17. In combination, an automobile body including a window opening having a movable closing panel therefor in the plane thereof when closed and an ash receiving and ejecting device normally mounted in receiving position on one side of the plane defined by said window opening, mounting means for said device, and means to cause relative movement between said device and said mounting means and bodily movement of said device from a position on one side of said plane to a position on the other side of said plane, said last means being automatically actuated due to movement of said panel to move said device to dumping position.

18. In combination, an automobile body including a window opening and a rotatably mounted ash receiving and ejecting device normally mounted in receiving position on one side of the plane defined by said window opening, means mounting said device for bodily movement relative to said mounting means from said receiving position on one side of said plane to a dumping position on the other side of said plane, and means automatically actuated due to movement of said panel to open position to rotate said device to dumping position.

19. In combination, an automobile body including a window opening and an ash receiving and ejecting device normally mounted in receiving position on one side of the plane defined by said window opening, means mounting said device for bodily movement on a horizontal axis from a position on one side of said plane to a position on the other side of said plane, and means connected to said device and cooperating with said mounting means for moving said device to dumping position.

20. In combination, an automobile body including a side window opening and movable panel therefor, and an ash receiving and ejecting device to be mounted in receiving position on one side of the plane defined by said window opening, a supporting means, means mounting said device on the supporting means on a horizontal axis whereby the device may have bodily movement from a position on one side of said plane to a position on the other side of said plane, and means automatically actuated by relative movement between said panel and opening to move said device on the horizontal axis relative to the supporting means to dumping position.

JOHN M. KISSELLE.
